UNITED STATES PATENT OFFICE.

HENRY J. MEADER, OF UTICA, NEW YORK.

REFINING-ENGINE.

1,125,583.

Specification of Letters Patent.

Patented Jan. 19, 1915.

Application filed March 10, 1914. Serial No. 823,801.

To all whom it may concern:

Be it known that I, HENRY J. MEADER, a citizen of the United States, residing at No. 12 Kernan avenue, Utica, in the county of Oneida and State of New York, have invented certain new and useful Improvements in Refining-Engines, of which the following is a specification, reference being had therein to the accompanying drawing.

10 My invention relates to an improved refining engine, and I declare that the following is a full, clear, concise and exact description thereof, sufficient to enable one skilled in the art to make and use the same, 15 reference being had to the accompanying drawings in which like reference characters refer to like parts throughout.

16 The device of the invention relates particularly to refining engines used in paper mills and which are commonly known as Jordan engines.

17 The object of the invention is to provide a more satisfactory and permanent filling, as it may be called, meaning thereby the 25 parts which, in the construction of the engine, are placed between the blades.

18 The engine consists in general construction of a conical case in which is revolved a conical core which may be of solid construction or made hollow. On the inner surface of the case and the outer surface of the core are mounted a series of blades running lengthwise the case and the core throughout the length or part of the length 35 according as the shape of the case and the core permit without too close crowding of the blades. These blades consist of metal strips of given thickness and width which are securely mounted on their respective surfaces. There are a variety of means in use whereby these blades may be mounted firmly in position, unless they may be made integral with the respective body of which they are parts. Between these blades is placed 40 what is called the filling parts, commonly of wood, being in the form of a single strip running lengthwise the case or the core and filling the space between the blades. It has been found most expedient to use wood for 45 this filling as most adaptable for the purpose on account of its inherent qualities. It is found, however, that in the revolution of the core the stock which passes through the engine or beater is thrown violently 50 against one side of each blade and against

the face of the filling adjacent to that blade. This action wears the filler away at one edge while it is worn very little at the other edge and, therefore, the filler requires frequent replacing.

55 My invention provides a new style of filler which embodies the desirable features of the wooden filler and at the same time obviates the severe wear of the ordinary wooden filler.

60 In the drawings, Figure 1 is a longitudinal sectional view of a case with a core mounted therein in full view; Fig. 2 is a sectional view transverse the axis showing a part of the case and part of the core with 65 some of the blades and filler thereon, and Fig. 3 is a full side view of part of the core showing the blades and my improved filler therebetween.

65 Referring to the figures in detail, A represents the case, B the core and D the revolute shaft which carries the core. The several blades on the case are represented by 1 and those on the core are shown by 2. It will be understood that any suitable 70 means may be employed for the mounting of these blades and I, therefore, do not represent any particular means as a person ordinarily skilled in the art may make his own selection.

75 Referring to Fig. 2, the small arrows indicate the general direction of the flow of the stock passing through the engine, showing that the stock is naturally thrown against the blade and the filler at about the points 80 indicated. In my improved construction I build the filler of two parts, one indicated by 3 and preferably made of wood and the other indicated at 4 and preferably made of iron. I have found by actual practice that 85 using a strip of iron, 4, to occupy the place where the wear comes upon the filler and using a strip of wood, 3, to fill the rest of the space between the blades accomplishes the perfect holding and stiffening of the 90 blades and at the same time preserves the features which pertain to the use of wood fillers but obviates the wear which makes them of such short life.

95 I have indicated in Fig. 3, by 5 and 6, 105 bands which may be employed to hold the filler in place, but the illustration is simply indicative of any suitable means for holding them, and I do not confine myself to any particular method or means.

Having described my invention, what I claim as new and desire to secure by Letters Patent, is:

1. In a paper stock refining engine the combination of a blade supporting member, blades thereon spaced apart from one another and fillers between said blades, said fillers each composed of two members one of hard material at the side of the blades that receives the stock and adapted to resist wear therefrom and the other of a relatively porous material occupying the remaining space and adapted by its absorption of water to expand and tightly hold the blades and filling members circumferentially.
2. In a paper stock refining engine the combination of a blade supporting member, blades thereon spaced apart from one another and fillers between said blades, said fillers each composed of two members one of metal at the side of the blades that receives the stock and adapted to resist the wear therefrom and the other of wood occupying the remaining space and adapted by its absorption of water to expand and tightly hold the blades and filling members circumferentially.
3. In a paper stock refining engine the combination of a blade supporting member, blades thereon spaced apart from one another and fillers between said blades, said fillers each composed of two members one

of metal at the side of the blades that receives the stock and adapted to resist the wear therefrom and the other of wood occupying the remaining space and adapted by its absorption of water to expand and tightly hold the blades and filling member in place.

4. In a paper stock refining engine the combination of a core, blades mounted longitudinally thereon in spaced relation and fillers between said blades each composed of two members one of metal at the side of the blade that receives the stock and adapted to resist the wear therefrom and the other of wood adapted by its absorption of water to expand and tightly hold the blades and fillers circumferentially of the core.

5. In a paper stock refining engine the combination of a core, blades mounted longitudinally thereon in spaced relation and fillers between said blades each composed of two members one of metal at the side of the blade that receives the stock and adapted to resist the wear therefrom and the other of wood adapted by its absorption of water to expand and tightly hold the blades and fillers in place on the core.

In testimony whereof I hereunto affix my signature in the presence of two witnesses.

HENRY J. MEADER.
